UNITED STATES PATENT OFFICE.

BENJAMIN F. FERTICK, OF COLUMBUS, OHIO, ASSIGNOR TO JOSEPH A. JEFFREY, OF SAME PLACE.

GAS-REGULATOR.

SPECIFICATION forming part of Letters Patent No. 368,331, dated August 16, 1887.

Application filed March 30, 1887. Serial No. 232,993. (No model.)

To all whom it may concern:

Be it known that I, BENJAMIN F. FERTICK, a citizen of the United States, residing at Columbus, in the county of Franklin and State 5 of Ohio, have invented certain new and useful Improvements in Gas-Regulators, of which the following is a specification, reference being had therein to the accompanying drawings.

Figure 1 is a central vertical section of a 10 regulator embodying my improvement. Fig. 2 is a horizontal section on line *x* *x*, Fig. 1. Fig. 3 is a horizontal section on line *y* *y*, Fig. 1. Like reference-letters indicate like parts in all the figures.

15 A is the lower part of the body.

B is the inlet-pipe through which gas is admitted, and is preferably attached to the outlet-pipe of the meter; but it may be placed at any convenient point.

20 C is the intermediate part of the body, made funnel-shaped, and at its lower end fitting the upper end of the part A, which may also be funnel-shaped, as shown.

D is the upper part of the body, and E is 25 the cap or cover.

By making the sections A C D all funnel-shaped—that is, so shaped that the walls converge downwardly—I effect a saving of material, attain convenience in putting them together by solder or otherwise, and make a more artistically-shaped body.

30 *a* is the outlet for the discharge of such material as may be deposited or accumulate at that point, there being a pocket or trap formed there by reason of the inlet-tube B projecting some distance above the bottom of the lower section, A, of the body.

F is a transverse partition or diaphragm, below which is an inlet-chamber, F'. G is a 40 similar transverse partition, there being an outlet-chamber between the two partitions, and marked G'.

45 *g* is a tube projecting upward from the diaphragm G and substantially concentric to the walls of the body of the device.

H is a smaller tube within the tube *g* and concentric thereto, but longer, and extending down through the outlet-chamber and the diaphragm F some distance into the inlet-chamber F'.

50 *h* is a V-shaped upward-inclined slot or

throat formed in that part of the tube H which projects below the diaphragm F.

I is a gasometer or hollow funnel-shaped float, the lower open end of which fits somewhat closely to the outer surface of the tube *g*. 55

J *j* is a valve fitting closely inside the lower end of the tube H, the downward-projecting tubular flanged part *j* of the valve engaging with the inner surface of the tube, so as to insure a proper working relation between these parts. 60

J' is a valve-rod formed in two parts, and hinged at *j'*, the upper end of the rod being firmly connected with the upper part of the 65 float, preferably by means of nuts *j'j'* and a packing-washer or other contrivance to prevent leakage. When the valve is made tubular, as described, or formed with a downwardly-extending tubular flange or with other equivalent devices, it is provided with a long bearing on the valve-tube, and this, in conjunction with the hinging of the two parts of the valve-rod, avoids all cramping or binding of the valve if the float should oscillate, as it frequently does. 70

K K' is a duplex coiled spring, of which the part K is so much larger in cross-diameter than the part K' that there shall be no interference when in practical operation. 80

L is a screw-threaded rod. 85

M is a bracket or supporting bar or plate supported upon or within the upper end of the body. The threaded rod passes through the bracket or bar M, and carries two adjusting-nuts, *l l*, by means of which the vertical position of the bar relative to the other part may be determined.

When preferred, the valve J may be screwed onto the lower end of the valve-rod or otherwise adjustably attached to it. 90

95 My object in making the spring in two concentric coils is to secure a desired flexibility, elasticity, and freedom of movement; but I do not wish to be limited to the use of such double spring, because under many circumstances and conditions an ordinary single spiral spring will answer a very good purpose.

In operating my invention I purpose to fill the chamber D', which is above the diaphragm 100 or partition G, with glycerine or other suitable liquids up to about the point indicated by the

dotted line O, or thereabout, part of the liquid of course rising up through the lower open end of the float I.

Of course the buoyancy of the air within the gasometer will tend to lift the valve above the upper end of the V-shaped slot h, and thus prevent gas from passing through the tube H; but the position of the valve can be adjusted, so that under ordinary circumstances it will remain at some distance below the upper end of that slot. Therefore gas will flow in through the inlet-tube B, thence through slot h, out at the upper end of tube H into the float, down through the annular space between the tubes 15 g H into the outlet-chamber G', and thence through the eduction-tube e.

As will be readily understood, the pressure within the float will tend to lift it out of the surrounding liquid and close or partially close 20 the valve, thus reducing the size of the passage-way for gas through the V-shaped slot; and the consequent closing of the valve can be so regulated by means of the adjusting devices and the depth of the liquid as to maintain a practically-uniform pressure of gas at 25 the burner.

While I prefer to use a V-shaped slot in the tube H, with a valve, J j, and a cap or plate, h', closing the lower end of the tube, yet I do 30 not wish to be limited thereby, because many modifications of these parts might be adopted by any skilled mechanic without departing from the spirit of my invention.

I am aware of the fact that use has been 35 made heretofore in gas-regulators of a materially-different type of a float with downwardly-converging walls, in combination with an interior body or casing for the liquid-chamber, also having downwardly-converging walls; 40 but the regulators so used have been differently constructed from the one herein and have operated upon a different principle, in that the chamber within the float has been merely a recoil-chamber—that is to say, not a 45 chamber into which all of the gas is taken in a current and from which it is withdrawn as it passes to the burners, but one in which a volume of gas is retained more or less permanently, with the expectation that its pressure 50 will vary sufficiently to properly modify the volume of incoming gas. In the present device the parts are so constructed and related that all of the gas is carried from the inlet-orifice to the interior of the float, and is thence 55 taken to the eduction-pipe, so that the float is much more easily affected by any variation in the pressure of the gas than is the case where the float is simply a recoil-chamber, and by hav-

ing the exterior casing or body formed with downwardly-converging or conical walls I can 60 not only insert and attach the various tubes with ease, but can also dispense with a large part of the glycerine or liquid which has been heretofore necessary in devices of this sort.

What I claim is—

1. In a gas-regulator, the combination of the inclosing-body, the diaphragm F, the tube H, rising therefrom and projecting below the diaphragm and provided with the V-shaped slot, the float, and the valve arranged within 70 the tube H, substantially as set forth.

2. In a gas-regulator, the combination of the inclosing-body, the inlet-duct, the liquid-chamber, the float therein, the valve-tube extending continuously from the inlet duct or chamber to the interior of the float, said tube having a tapering passage-way through its wall at or near its lower end to vary the amount of gas admitted, the concentric tube extending from the interior of the float to the outlet-duct, 80 the valve situated in the said valve-tube and connected with the float, and the adjusting-spring connected with the float, substantially as set forth.

3. In a gas-regulator, the combination of 85 the liquid-chamber having downwardly-converging walls, the float therein having downwardly-converging walls, the inlet duct or chamber, the valve-tube extending continuously from the inlet duct or chamber to the interior of the float, through which all of the gas 90 is taken into said float, the outlet-duct from the interior of the float, the valve in the said valve-tube connected with the float, and the spring connected with the float, substantially 95 as set forth.

4. In a gas-regulator, the combination, with the gas-passages, the float, and the valve-tube having its upper end opening into the float, and provided at its lower end with a horizontal gas-inlet, of the imperforate valve arranged 100 inside said tube, substantially as set forth.

5. In a gas-regulator, the combination, with the gas-passages and the outlet-duct, of the float, the valve-tube, the valve below the float 105 having a tubular flange fitted to the valve-tube, and the rods hinged together and joining the float to the valve, substantially as and for the purposes set forth.

In testimony whereof I affix my signature in 110 presence of two witnesses.

BENJAMIN F. FERTICK.
